UNITED STATES PATENT OFFICE

ERIC W. ERICSSON, OF BROOKLYN, NEW YORK

SAFETY RAZOR

Application filed March 15, 1930. Serial No. 436,161.

This invention relates to safety razors and particularly to devices of this class employing blades having double cutting edges disposed for use at opposite sides of the holder; and the object of the invention is to provide improved means for mounting the blade in connection with the holder in such manner as to support the cutting edge thereof in a curved plane with reference to the edge of the guard or guards of the holder to provide a clearance space between the blade and guard facilitating free shaving operations as well as the passage of lather beneath the blade, thus increasing the utility of the device; a further object being to provide means whereby the corner portions of the blade may be supported in close relation with respect to the adjacent parts of the guard or prevent or obviate, to a major degree, accidental cutting of the skin in shaving operations; a further object being to provide a razor of the class specified with a shim or spacing member disposed between the blade and the guard to provide a clearance space for the lather between the blade and guard and also to facilitate the depression of the corner portions of the blade; and with the these and other objects in view, the invention consists in a device of the class and for the purpose specified, which is simple in construction, efficient in use, and which is constructed as hereinafter described and claimed.

The invention is fully disclosed in the following specification, of which the accompanying drawing forms a part, in which the separate parts of my improvement are designated by suitable reference characters in each of the views, and in which:—

Fig. 1 is a plan view of a razor made according to my invention.

Fig. 2 is a section on the line 2—2 of Fig. 1 on an enlarged scale.

Fig. 3 is a section on the line 3—3 of Fig. 2; and,

Fig. 4 is a perspective view of a shim which I employ.

In the drawing, I have shown at 10 the guard of the razor, 11 the cap or clamp for retaining the blade 12 within and between the guard and cap by the action of the handle member 13 which is in screwed threaded engagement with a threaded stem 14 constituting part of the cap 11, said cap also having spacing and alinement pins 15 disposed at opposite sides thereof and which are adapted to pass through apertures in the blade 12 and guard 10.

The guard 10 is semi-circular in cross sectional form, and the side edges thereof are notched at spaced intervals to provide a series of spaced teeth 16 which form the guards proper for the cutting edges 12a at opposite sides of the blade 12, and the cap 11 is also arc-shaped in form in cross section, the curvature thereof being different from that of the guard 10 so as to bring the side edges 11a thereof into engagement with the blade to flex the side edges of the blade in moving the same or the cutting edges 12a thereof into proper relation with respect to the guard or the teeth thereon.

In practice, the side edges 11a, instead of being straight as in other devices of this class are arc-shaped in form when viewed at either side edge of the device, the curvature of one side edge being indicated at 11b in Fig. 2 of the drawing. By virtue of this construction, the blade 12 or the cutting edges 12a thereof may be supported and reinforced in the arc-shaped position shown in order to provide a greater clearance between the cutting edges 12a and the guard centrally of the side edges of the razor than at the end or corner portions thereof, thus providing a better cutting edge at the central portion of the side edges of the razor and permitting the free passage of the lather beneath the razor blade.

To insure the support of the blade 12 in the manner above described, I employ a spacing

member or shim 17 which is disposed between the lower face of the blade 12 and the guard 10, the shim being preferably of the general form seen in detail in Fig. 4 of the drawing, the corner portions 18 thereof being cut away in order to permit the corner portions of the cap 11 to engage and depress the corresponding corner portions of the blade 12 at the cutting edges 12a thereof in flexing the blade into arc-shaped formation and in rigidly supporting the blade in this position, it being understood that the blade is backed by the cap 11. It is also preferred that the side edges 19 of the shim 17 be cut out at intervals as seen at 20 to provide clearance spaces for the lather in the operation of shaving. Said shim is provided with a central aperture 21 through which the threaded pin 14 passes and with other apertures 22 at opposite sides of the aperture 21 through which the guide pins 15 are free to pass.

It will be understood that the thickness of the shim 17 will to a degree, govern the spacing of the cutting edges 12a of the blade with respect to the guard as will also the contour 11b at the side edges 11a of the cap 11, and these may be arranged to provide the most effective shaving operations suitable for beards of various kinds.

30 It will be understood that while I have shown my invention as applied to a razor of specific construction that my invention is not necessarily limited in this respect, and various changes in and modifications of the construction herein shown and described may be made within the scope of the appended claims, without departing from the spirit of my invention or sacrificing its advantages.

Having fully described my invention, what 40 I claim as new and desire to secure by Letters Patent, is:—

1. A safety razor having a guard, a cap movable with respect to the guard and a blade arranged between the guard and cap, means 45 for flexing the corner portions of the cutting edge of the blade to arrange said cutting edge in a curved path to space the central portion of the cutting edge a greater distance from the guard centrally thereof than at the end 50 portions of the blade, the edge of the cap engaging said blade being fashioned to conform with the flexed curvature of the blade, and said means comprising a shim disposed between the guard and blade, the corner portions of said shim being removed to permit the flexure of the corner portions of the blade in securing the same in position.

2. A safety razor having a guard, a cap movable with respect to the guard and a blade 60 arranged between the guard and cap, means for flexing the corner portions of the cutting edge of the blade to arrange said cutting edge in a curved path to space the central portion of the cutting edge a greater distance from the guard centrally thereof than at the end 65

70 portions of the blade, the edge of the cap engaging said blade being fashioned to conform with the flexed curvature of the blade, said means comprising a shim disposed between the guard and blade, the corner portions of said shim being removed to permit the flexure of the corner portions of the blade in securing the same in position, the edge of the guard arranged longitudinally of the cutting edge of the blade being divided into a plurality of longitudinally spaced teeth, and the corresponding edge of the shim being recessed.

3. A spacing shim for safety razors of the class described comprising an elongated body 80 of thin sheet material, said body being apertured to key the same with respect to parts of the razor blade holder and the corner portions of said shim being removed to form concaved corner edges, the transverse dimensions 85 of said shim being substantially the same as the blade of the razor, and opposite side edges of said shim having spaced recesses.

4. A safety razor having a guard provided with straight side edges, a cap movable with respect to the guard and a blade adapted to be arranged between the guard and cap, the corner portions at the side edges of said cap being lower than the central portion of said side edges, and means disposed beneath the 95 blade whereby in moving the cap toward the guard, the corner portions of said cap will depress the corner portions of the blade to flex the cutting edge thereof in a curved path, disposing the central portion of the cutting edges of the blade a greater distance from the guard centrally thereof than at the corner portions.

5. A safety razor having a guard provided with straight side edges, a cap movable with respect to the guard and a blade adapted to be arranged between the guard and cap, the corner portions at the side edges of said cap being lower than the central portion of said side edges, means disposed beneath the blade 100 whereby in moving the cap toward the guard, the corner portions of said cap will depress the corner portions of the blade to flex the cutting edge thereof in a curved path disposing the central portion of the cutting edges 105 of the blade a greater distance from the guard centrally thereof than at the corner portions, and the side edges of the cap conforming with the curved flexure of the cutting edge of the blade to form a substantially rigid backing 110 for the cutting edges of the blade.

6. A safety razor having a guard provided with straight side edges, a cap movable with respect to the guard and a blade adapted to be arranged between the guard and cap, the corner portions at the side edges of said cap being lower than the central portion of said side edges, means disposed beneath the blade 115 whereby in moving the cap toward the guard, the corner portions of said cap will depress 120

the corner portions of the blade to flex the cutting edge thereof in a curved path, disposing the central portion of the cutting edges of the blade a greater distance from the guard 5 centrally thereof than at the corner portions, and said means comprising an elongated plate, the corner portions of which are removed, permitting the depression of the corner portions of said blade.

10 In testimony that I claim the foregoing as my invention I have signed my name this 12th day of March, 1930.

ERIC W. ERICSSON.
